UNITED STATES PATENT OFFICE

MAURICE E. REAGAN, OF PITTSBURGH, PENNSYLVANIA, ASSIGNOR TO WESTINGHOUSE ELECTRIC & MANUFACTURING COMPANY, A CORPORATION OF PENNSYLVANIA

AUTOMATIC SECTIONALIZING SWITCH

Application filed September 16, 1921. Serial No. 501,156.

My invention relates to automatic reclosing circuit interrupters and particularly to devices generally known as sectionalizing switches.

One object of my invention is to provide a circuit interrupter for connecting circuits or sections of a circuit that will open upon the occurrence of a predetermined overload or short-circuit on either section, or voltage failure on the system, and that will not close so long as the overload or short-circuit condition in either section, or the low voltage on the system, remains, but which will close when the overload or short-circuit condition is removed and the potential conditions of both circuits or sections again becomes substantially normal.

Another object of my invention is to provide a structure of the above-indicated character wherein the reclosing of the sectionalizing switch is controlled in accordance with the value of the resistance connected to, and included in, one of the sections.

A further object of my invention is to provide means whereby, upon the opening of the sectionalizing switch by reason of the occurrence of a short-circuit, the resistance of the faulty section may be measured and the reclosing of the sectionalizing switch controlled in accordance with the value of such resistance.

Another object of my invention is to provide a system of the above-indicated character, that shall be operative whether both sections or circuits are being independently supplied with energy or whether only one section is so supplied.

A still further object of my invention is to provide a system, of the above-indicated character, wherein standard apparatus of a rugged character may be employed that shall be relatively simple and inexpensive in its construction, and reliable and effective in its operation.

Co-pending application Serial No. 375,965, filed April 23, 1920, by J. H. Procter, and assigned to the Westinghouse Electric & Manufacturing Company, which has since matured into United States Patent No. 1,632,983, discloses an automatically reclos-

ing circuit interrupter, the reclosing of which is controlled by a Wheatstone bridge when the load that is connected to the circuit controlled by the interrupter attains a predetermined value.

In practicing my invention, I employ the principle disclosed in the aforementioned application and apply it to the control of a sectionalizing switch. I so arrange a plurality of resistors and control relays that, upon the opening of the sectionalizing switch because of abnormal conditions in either section, the resistors are connected to the faulty section to compose a Wheatstone bridge, one arm of which comprises the resistance of the conductors of one section and of the load connected thereto. When the resistance of the load that is connected to the faulty section attains a predetermined value, indicating the passage of abnormal conditions, the sectionalizing switch is reclosed.

Figure 1 of the accompanying drawings is a simplified diagrammatic view of a sectionalizing switch and the control apparatus associated therewith.

Fig. 2 is a modification of Fig. 1, and illustrates the arrangement of additional resistors for the relay switches, and

Fig. 3 is a simplified diagrammatic view illustrating schematically the arrangement of the various resistors under predetermined conditions in the system illustrated in Figs. 1 and 2.

In Fig. 1 are illustrated two circuits or sections 1 and 2, respectively, that are adapted to be connected by a circuit interrupter 3. The interrupter 3 comprises a plurality of contact members 4 and 5, the engagement of which is effected and maintained by an operating coil 6. The circuit of the operating coil 6 is controlled, at one point, by a switch 7 that is controlled by an overload relay 8 in accordance with the value of current that is exchanged between the sections 1 and 2.

A resistor 9, having a resistance of relatively large value, is connected between the sections 1 and 2 in shunt relation to the contact members 4 and 5 of the interrupter 3 and serves to preclude the exchange of current between the two sections in excess of a prede-

terminated value, after the interrupter 3 has been opened by reason of the occurrence of an overload or short-circuit upon either of sections 1 and 2.

5 The operating coils of two relay devices 10 and 11 are respectively connected between the section conductors 1 and 2 and a return conductor 12 through a resistor 13 of relatively low resistance.

10 The relay device 10 is provided with three switches 14, 15 and 16 that are closed when the relay device is energized to a predetermined degree and that are open when the coil of the relay device is energized less than a predetermined degree.

15 The relay device 11 is similarly provided with switches 17, 18 and 19 that are similarly maintained in closed or in open position, according to whether the operating coil of the 20 relay is energized to a sufficient degree or not.

25 One contact member of the switch 14 and one contact member of the switch 15 are connected to the section conductor 1, and, similarly, one contact member of the switch 17 and one contact member of the switch 18 are connected to the section conductor 2. The other contact members of the switch 14 and of the switch 17 are connected by a conductor 20. Similarly, the other contact members of the switch 15 and of the switch 18 are connected by a conductor 21.

30 The switch 16 is connected, in series with the switch 7, to the conductor 20, by means of conductors 22 and 23. The corresponding switch 19 of the relay device 11, when closed, serves to connect one terminal of the operating coil 6, of the sectionalizing switch 3, to the return conductor 12.

35 Upon the closure of either the switch 15 or the switch 18, a resistor 24, having a resistance of relatively large value, is connected in series with the resistor 13 between the section 1 and return conductor 12 or between the section 2 and the return conductor 12.

40 Assuming the occurrence of a short circuit between the section conductor 2 and the conductor 12, current will tend to flow through the circuit from the section conductor 1, through the relay 8 and the sectionalizing switch 3, to the section 2.

45 When the value of such current exceeds a predetermined value at which the overload relay 8 is set to operate, the switch 7 will open. The operating coil 6 is thereupon deenergized and the sectionalizing switch 3 is opened. The switch 3 being open, current from the section conductor 1 may be supplied to the short-circuit on the section 2 through the resistor 9 that has a relatively large value of 50 resistance.

55 Since the section 1 is normal, the voltage of that section will be sufficient to maintain the operating coil of the relay device 10 energized to maintain the switches 14, 15 and 16 closed. The relay device 11, however, is not sufficient-

ly energized to maintain its switches 17, 18 and 19 closed.

60 By reference to the diagram in Fig. 3, it will be seen that the resistors 24, 13 and 9 constitute three arms of a Wheatstone bridge of which the section conductor 2, the short circuit therein and the load connected thereto constitute the fourth arm. The operating coil of the relay device 11 corresponds to the galvanometer that is connected between 75 equi-potential points of a Wheatstone bridge.

70 When the resistance of the circuit, including the section conductor 2, the load connected thereto and the short-circuit therein, increases to a predetermined value, the operating coil of the relay device 11 will effect the closure of its switches 17, 18 and 19. The 75 circuit of the operating coil 6 will thereupon be completed and the sectionalizing switch will be reclosed. It will be observed that both 80 relay devices 10 and 11 must be closed to effect the energization of the operating coil 6.

85 By arranging the values of the resistance of the resistors 9, 13 and 24 to bear certain relations with respect to each other, the relay 11 may be caused to operate for any predetermined value of resistance that may be connected to the section 2. By so arranging the 90 various resistors that the relay 11 will be closed only when the resistance connected to the circuit section 2 exceeds a predetermined value, the switch 3 will be precluded from reclosing until the short-circuit conditions are 95 clear and the load connected to the section exceeds a predetermined value. Although the 100 relay 11 is illustrated as of the circuit-closing type, it is obvious that the resistors may be so arranged as to permit the employment of a circuit-opening or drop-out switch which will be de-energized when the resistors are balanced.

105 If the short-circuit conditions occur upon the section 1, the relay 11 will remain energized to maintain its switches 17, 18 and 19 closed, and the switches 14, 15 and 16 will remain open. The section conductor 1 and the load connected thereto will then constitute the fourth arm of the Wheatstone bridge composed of the resistors 9, 13 and 24, and the 110 relay device 10 will constitute the controlling 115 element.

115 By means of such an arrangement, comprising a Wheatstone bridge, it will be observed that a very accurate measurement of the load resistance may be effected, and the 120 operation of the control relay devices 10 and 11 may be rendered correspondingly sensitive.

125 In the arrangement illustrated in Fig. 2, the various elements that are employed are similar in character to those illustrated in Fig. 1, and the operating coils of the relay devices 10 and 11 are provided with limiting resistors 26 and 27. The function of the resistors 130 26 and 27 is to limit the value of current that

may traverse the coils 10 and 11 when the entire system is operative, in order to reduce the heating and the losses within those coils. The resistors 26 and 27 are connected in series with the coils 10 and 11 and the corresponding section conductors 1 and 2.

The value of the resistors 26 and 27 is so calibrated that sufficient current will be permitted to traverse the coils 10 and 11 to maintain the switches in closed position only after the actuation of the switches to such positions. The value of current that may traverse the coils while the resistors are effectively inserted in circuit therewith is insufficient to effect the actuation of the relay devices to close the switches.

In order to permit the operating coils of the relays 10 and 11 to be sufficiently energized to close the corresponding switches, the resistor 26 is short-circuited by two switches 28 and 29, and the resistor 27 is similarly short-circuited by two switches 30 and 31.

The switches 28 and 30 are closed when the sectionalizing switch 3 is open and are open when the sectionalizing switch 3 is closed.

The switches 29 and 31, similarly, are closed when the relay devices 10 and 11 are in their de-energized, or open, positions, and the switches are opened when the relays 10 and 11 are in their energized, or closed, positions.

Thus, when the sections 1 and 2 are supplied with energy at normal voltage, sufficient current traverses the operating coils of the relays 10 and 11 to effect the closing of the associated switches. The switches 29 and 31 are arranged to open when the movable members of the associated relay devices are almost at the end of their travel. At that position, the value of current that is permitted to traverse the coils 10 or 11 is sufficient to maintain the switches closed.

Two resistors 32 and 33 are provided in circuit with the switches 15 and 18 of the relays 10 and 11 to preclude an excessive current from traversing those switches when they are closed by the energization of the associated relays before the closure of the main switch 5 is effected.

By employing a measuring system such as that illustrated and described, the reclosing of the sectionalizing switch may be accurately controlled in accordance with a predetermined value of resistance in the sections that are connected by the switch.

My invention is not limited to apparatus of the specific type illustrated or to the particular arrangement of such apparatus since various modifications may be made therein within the spirit and scope of the invention, as set forth in the appended claims.

I claim as my invention:—

1. In an automatically-reclosing sectionalizing circuit-controlling system, means for connecting two circuit sections, means, in-

cluding a Wheatstone bridge, for controlling the connecting means, and means for connecting the Wheatstone bridge selectively to either circuit section.

2. In an automatically-reclosing sectionalizing circuit-controlling system, the combination with means for connecting two circuit sections, of means, including a resistance-measuring device, for controlling the connecting means, and means for automatically connecting the resistance-measuring device selectively to either section.

3. An automatically-reclosing sectionalizing circuit-controlling system including means for connecting two circuit sections, of means whereby the connecting means is energized from one of the sections, a resistance-measuring means for controlling the connecting means, and means responsive to the conditions of both circuit sections for automatically connecting the resistance-measuring means selectively to either section.

4. A control system for a sectionalizing switch between two section conductors including a plurality of resistors arranged to constitute a Wheatstone bridge, one arm of which includes one section conductor and the load connected thereto, and means for connecting the bridge selectively to either section conductor.

5. An automatically-reclosing sectionalizing circuit-controlling system having means for connecting two circuit sections and means whereby one section conductor and the load connected thereto are connected to a network of resistors to constitute a Wheatstone bridge, means responsive to a predetermined balance therein for controlling the connecting means, and means for establishing the Wheatstone bridge by connecting the resistors selectively to either circuit section.

6. An automatically-reclosing sectionalizing circuit-controlling system having means for connecting two circuit sections and means responsive to the conditions of both circuit sections whereby either section conductor and the load connected thereto are selectively connected in circuit with a resistance-responsive means, and means controlled by the resistance-responsive means for controlling the connecting means.

7. The combination with two adjacent section conductors of a distributing system and a main contact member for connecting the conductors when in closed position, of a limiting resistor connected between the sections to limit the exchange of current therebetween when the main contact member is open, two auxiliary resistors, a relay switch energized from each section conductor and responsive to the potentials thereof, one of the relay switches operating to connect the auxiliary resistors to the associated section conductor to complete a Wheatstone bridge arrangement and the other relay switch operating as the

potential-responsive element of the bridge thus constituted by the resistors and the other section conductor and connected load.

8. An automatically-reclosing sectionalizing circuit-controlling system including means for connecting two circuit sections, a resistance-measuring device including a comparison resistor of predetermined value for determining the value of load resistance in either section at which the connecting means shall operate and automatic means for connecting the resistance-measuring device selectively to either section.

15 9. An automatically-reclosing sectionalizing circuit-controlling system including means for connecting two circuit sections, means comprising a resistance-responsive device, for controlling said connecting means and means for automatically applying the resistance-responsive device selectively to either section.

20 10. An automatically-reclosing sectionalizing circuit-controlling system having means for connecting two circuit sections, means including a resistance-comparing device for controlling the operation of said connecting means and means responsive to the electrical condition of both circuit sections for controlling the application of the resistance-comparing device selectively to either circuit section.

25 11. An automatically-reclosing sectionalizing circuit-controlling system including means for automatically connecting two circuit sections, means for controlling said connecting means having a potential-balance arrangement and means responsive to the condition of both circuit sections for controlling the application of the balance arrangement selectively to either section.

30 12. An automatically-reclosing sectionalizing circuit-controlling system including means for automatically connecting two circuit sections, operating means therefor, means energized from both sections and arranged to constitute a resistance-measuring device, when the sections are not connected by the connecting means, to control the energization of the operating means, and means for applying the resistance-measuring device selectively to either circuit section.

35 13. The combination with two adjacent circuit sections normally individually energized, connecting means therebetween comprising an operating coil, of an overload device for opening the circuit of the operating coil upon a transfer of excess current between the two sections, and reclosing means comprising a Wheatstone-bridge circuit for measuring the resistance of either section and means operative under predetermined voltage conditions in both sections for directly effecting the energization of the operating coil and operative under other voltage conditions for effecting the energization of the operating coil de-

pendent upon one section and the load connected thereto attaining a predetermined value of resistance, regardless of the voltage of the other section.

40 In testimony whereof, I have hereunto subscribed my name this 6th day of September, 1921.
